EDUCATIONAL TOY DEVICE

Max J. Ruderian, 613 Wilshire Blvd., Santa Monica, Calif.
Filed Oct. 25, 1962, Ser. No. 233,089
6 Claims. (Cl. 273—142)

This invention generally relates to an educational toy device and more particularly concerns a self-assembled or "do-it-yourself" type education toy which may be readily constructed from conveniently available materials and which—in one form—may be embodied in the sidewalls of a cereal box, pancake box, or the like as a premium item.

Although the invention will be described from the standpoint of its application as a premium item or cutout from the sidewalls of a box, it will be appreciated that the toy device of the present invention may be formed in more permanent form from plastic, wood, heavy cardboard or the like, either in a final assembled form or in a construction lending itself readily to assembly by the user.

One of the objects of the present invention is to provide an educational toy device which is adaptable to a variety of educational type games, for example, of the matching type in which states are matched with capitals, inventors are matched with inventions, paintings are matched with artists, and the like.

Another object of the present invention is to provide an improved educational toy device which may be used in conjunction with games of chance in a manner similar to roulette, for example.

Still another object of the present invention is to provide an educational toy device which may be readily assembled from a limited number of parts and yet which is susceptible of inexpensive fabrication from relatively lightweight cardboard such that it may be imprinted on the sidewalls of a box or the like in the form of cutouts.

Another object of the present invention is to provide an educational toy device which is extremely economical to manufacture, which is simple to operate and yet which conforms with the foregoing objects.

Still a further object of the present invention is to provide an educational toy device which is so constructed as to retain a child's attention and yet of a design which requires only a minimum amount of skill to assemble and operate.

These and other objects and advantages of the present invention are generally achieved by providing an educational toy device which comprises a first annular flat member and a second annular flat member. The second annular flat member is substantially congruent to the first annular member and is designed to be super-imposed thereover.

A disc-shaped member is designed to be retained between the first annular member and the second annular member, and some form of cooperating locking means retains the disc-shaped member between the annular members in such a manner that the disc member may be rotated within the annular members.

In this regard, a plurality of discrete markings are provided on the disc-shaped member and other markings are provided on the annular members, whereby according to the disposition of the disc-shaped member within the annular members, certain markings on the disc-shaped member will be aligned with particular markings or indicia on the annular shaped members such that various educational games and games of chance may be played.

2

A better understanding of the present invention will be had by reference to the drawings, showing merely two illustrative embodiments thereof, and in which:

FIGURE 1 is an exploded perspective view of one embodiment of the educational toy device of the present invention;

FIGURE 2 is a view of a part of the educational toy device of FIGURE 1 in its form prior to partial assembly;

FIGURE 3 is a view of another part of the educational toy device of FIGURE 1 prior to assembly thereof;

FIGURE 4 is a plan view of the educational toy device of FIGURE 1 in its assembled form; and

FIGURE 5 is an exploded perspective view of another embodiment of the educational toy device of the present invention.

Referring now to the drawings, there is shown in FIGURE 1 a first annular member 10 substantially congruent and super-imposed over a second annular member 11. The annular members 10 and 11 are connected together at a point 12 which forms a rectilinear section. Thus, as seen in FIGURE 2, the annular members may be embodied in flat form on the sidewalls of a cereal box or the like from which they may be cut out to the shape of FIGURE 2 and folded back over to the form shown in FIGURE 1. As shown, each of the annular members defines a central circular open portion of diameter considerably greater than the width of the material surrounding the open portion.

Of course, as heretofore mentioned, members 10 and 11 may also be formed of other materials, for example, plastic, heavy cardboard, wood, or the like.

The members 10 and 11 are provided with finger holding tabs 13 and 14, respectively. In order to couple the members 10 and 11 together, the member 11 (in one form) is provided with a tab 15 designed to fit within a slot 16 of the member 10 in the manner as shown in FIGURE 1. Similarly, and conversely, the member 10 is provided with a tab 17 designed to fit within a slot 18 in the member 11. Desirably, the member 10 is provided with sector markings 19 to enclose certain printing or indicia, numbers, or the like for a purpose which will hereafter be explained.

A circular member is designed to be received between the annular members 10 and 11 and exposed through the central circular open portions thereof. As shown, the circular member may comprise a pair of superimposed discs 20 and 21 also congruent one with respect to the other. The discs 20 and 21 may be formed from flat cutouts joined together in the same manner as the annular members 10 and 11, for example as shown in FIGURE 3. In order to lock the discs 20 and 21 when they are positioned in super-imposed relationship, a tab 22 may be provided on the disc 20 which locks into an appropriate slot 23 on the disc 21 as shown clearly in the views of FIGURES 1 and 3.

In assembling the toy device in the embodiment shown in FIGURES 1-4, the annular members 10 and 11 are folded over at 12 and locked into position with the tab 15 fitting into the slot 16, as shown in FIGURE 1. Thereafter, the disc-shaped members 20 and 21 are locked together with the tab 22 fitting through the slot 23 and the super-imposed discs are then placed between the annular members 10 and 11. Thereupon, the tab 17 is locked into the slot 18 so that the discs 20 and 21 may be rotated

within the annular members 10 and 11 and retained therein by the locking tabs 15 and 17 in cooperation with the connected flat portion 12. The operator's fingers may be used to grasp the tabs 13 and 14. With such a construction, the center discs 20 and 21 may be spun or otherwise rotated to different positions to play games of chance or educational games.

The games are played in the same manner as with applicant's other educational toy device filed October 11, 1962, identified by Serial No. 229,871, entitled Dual Purpose Educational Toy Device, now Patent No. 3,136,552. Towards this end, the sector markings 24 (see FIGURES 1 and 4) may be provided on the discs 20 and 21 to be aligned with the appropriate sector markings 19 on the annular members 10 and 11. In this regard, there would also be markings 19 provided on the back of annular member 11 and also on the bottom of disc 21 (these markings not being shown in these drawings since they are the same as the markings 19 and 24, respectively). If desired, a window 25 may be provided in the annular member 10 to align itself with separate lettering, indicia, or numerals in the circumferential portion of the discs 20 and 21 such that three variables may be used: the markings on the discs 20 and 21 on the exposed portions thereof; the markings on the discs 20 and 21 on the concealed portions thereof; and the markings on the annular members 10 and 11. Thus, for example, an English word might be employed between the sectors 24 on the discs 20 and 21; an equivalent word might be set forth between the markings 19; and the German translation might be set forth on the concealed portion of the markings 24 under the annular members 10 and 11 as viewed through the window 25.

It will be appreciated that the tabs employed may be differently located and that they may be inter-changed with respect to the annular members 10 and 11 insofar as location of tabs and slots are concerned.

It will further be evident that certain changes and modifications may be made in the manner in which the discs are retained within the annular members.

Thus, there is shown in FIGURE 5 another embodiment wherein the educational toy device of the present invention includes an annular member 26 congruent to and super-imposed over another annular member 27. The annular member 26 is provided with a tab 28 designed to inter-lock in a slot 29 provided in the annular member 27. Finger tabs (not shown) may be appropriately provided.

Instead of providing locking tabs equivalent to tabs 15 and 17 as in the construction of FIGURE 1 in this embodiment the super-imposed disc members 30 and 31 are provided with radially inwardly disposed projecting tabs 32, 33, and 34. The tabs 32-34 are partial cutouts formed in the disc 30 which are bent upwardly out of the plane thereof on a given circumference designed to be aligned with the circumference of the inner diameter of the annular member 26.

Thus, the discs 30 and 31, after being super-imposed one over the other, are positioned between the annular members 26 and 27 and the tabs 32-34 engage the inner edge of the annular member 26 and are folded back thereover whereby the disc members 30 and 31 are journaled between the annular members 26 and 27. Of course, similar tabs are provided on the exposed side of the disc member 31 which are designed to cooperate with the inner periphery of the lower annular member 27.

It is apparent that with the latter construction, only a single locking tab 28 and cooperating slot 29 need be provided since the tabs 32-34 and the equivalent tabs on the exposed side of disc member 31 serve to journal and lock the discs 30-31 in position between the annular members 26 and 27.

The particular markings and cooperating indicia, symbols, words, and numbers and the manner in which they cooperatively function between the discs and the annular

members may be the same as that employed in conjunction with the embodiment of FIGURE 1.

From the foregoing, it will be appreciated that the educational toy device of the present invention presents an economical and simplified approach to the manufacture of an educational toy device from inexpensive materials yielding a structure appealing to a child susceptible of use in conjunction with educational games as well as games of chance, and yet a device which is adaptable to being embodied as a cutout or the like in a premium item, for example in conjunction with a cereal box or the like.

Although it will be appreciated that many changes and modifications may be made in the construction of the educational toy device of the present invention, as, for example, illustratively shown in FIGURE 5, it is believed that such changes and modifications come within the scope and spirit of the invention as set forth in the following claims.

What is claimed is:

1. An educational toy device comprising: a first annular flat member; a second annular flat member substantially congruent to said first annular flat member and super-imposed thereover; a first disc-shaped member; a second disc-shaped member, said second disc-shaped member being joined at one edge to said first disc-shaped member and folded back thereover in super-imposed relationship, said super-imposed disc-shaped members being positioned between said first and second annular members, said annular members defining central circular open portions of diameters greater than the widths of the annular material surrounding said open portions, said super-imposed disc-shaped members being exposed through said open portions; cooperating means between said annular members and said disc-shaped members rotatably journailling said disc-shaped member between said annular members; and, a plurality of discrete markings on the exposed sides of said disc-shaped members and on the exposed sides of said annular members designed to be, respectively, aligned with each other, according to the positioning of said disc-shaped members within said annular members for playing games of chance and educational matching games.

2. An educational toy device, according to claim 1, and means locking said first and second disc-shaped members together.

3. An educational toy device, according to claim 1, markings on said disc-shaped members about the peripheral portions thereof designed to underlie said annular shaped members; and, means on said annular members defining at least one window for viewing given markings of said peripheral portions of said disc-shaped members.

4. An educational toy device comprising: a first annular flat member; a second annular flat member substantially congruent to said first annular member and super-imposed thereover; finger tabs projecting from said first annular member and said second annular member, said finger tabs designed to be aligned with each other also in super-imposed relationship; a pair of disc-shaped members locked together and disposed between said first annular member and said second annular member, each annular member defining a central circular open portion of diameter greater than the width of the annular material surrounding said open portion, said pair of disc-shaped members being exposed through said open portion; cooperating means between said annular members and said disc-shaped members rotatably journailling said pair of disc-shaped members between said annular members; a plurality of discrete markings on said pair of disc-shaped members on the exposed sides thereof and on the exposed sides of said annular shaped members designed, respectively, to be aligned with each other in accordance with the positioning of said disc-shaped members within said annular shaped members.

5. An educational toy device, according to claim 4, further including means locking together said annular

members comprising a tab extending from at least one of said members and a slot provided in another of said members whereby said tab may be inserted through said slot and locked therein.

6. An educational toy device, according to claim 4, in which said cooperating locking means comprises tabs projecting from the exposed faces of said disc-shaped members, said tabs being designed to engage the inner diameter of said annular shaped members to lock said disc-shaped members within said annular shaped members for rotatable journalling therein.
